UNITED STATES PATENT OFFICE

WILFRED SHURTLEFF, OF MOLINE, ILLINOIS, ASSIGNOR TO THE HERMAN NELSON CORPORATION, OF MOLINE, ILLINOIS, A CORPORATION OF ILLINOIS

DESIGN FOR A PANEL FOR CONCEALED RADIATOR CABINETS

Application filed December 9, 1929. Serial No. 33,714. Term of patent 14 years.

To all whom it may concern:

Be it known that I, WILFRED SHURTLEFF, a citizen of the United States, residing at Moline, in the county of Rock Island and State of Illinois, have invented a new, original, and ornamental Design for Panel for Concealed Radiator Cabinets, of which the following is a specification, reference being had to the accompanying drawings, forming part of this specification.

In the drawings:

Fig. 1 is a perspective of a panel for concealed radiator cabinets embodying my new design;

Fig. 2 is an end view thereof.

I claim:

The ornamental design for a panel for concealed radiator cabinets, as shown.

WILFRED SHURTLEFF.
